UNITED STATES PATENT OFFICE.

SILVANUS F. VAN CHOATE, OF NEW YORK, N. Y.

IMPROVEMENT IN TELEGRAPH-MAGNETS.

Specification forming part of Letters Patent No. 38,774, dated June 2, 1863; antedated April 26, 1862

To all whom it may concern:

Be it known that I, SILVANUS F. VAN CHOATE, of the city, county, and State of New York, have invented certain new and useful Improvements in Magnets for Telegraphic and other Purposes; and I do hereby declare that the following is a full, clear, and exact description of the same, reference being had to the accompanying drawings, forming part of this specification, in which—

Figure 1 is a front view, full size, of my magnet arranged with sounders connected for the purposes of telegraphing and receiving messages by sound. Fig. 2 is an end view, full size, of Fig. 1. Fig. 3 is a vertical section of Fig. 1, taken in a plane parallel with Fig. 1 and at a point represented, in Fig. 2 by sectional line 3 and 4. Fig. 4 is a plan of that part of my magnet which is constituted of a fixed or natural magnet, showing its formation and connections with the coils removed. Fig. 5 is a plan of the electro or soft-iron part of the core, showing its formation, and representing its internal or flat face. Fig. 6 is a horizontal sectional view of the bearings of the axle of the armature lever taken in a plane at a point, as shown by sectional line 5 and 6 in Fig. 2, and at right angles to the vertical sectional line 3 and 4 in the same figure. Fig. 7 is a view of one of the arms of the cores, showing at 10 its segmental end, and at 12 the rabbeted end to be halved onto the part of the core marked H in Fig. 5. Fig. 8 is a vertical section of one of the coils or helices, taken at right angles to Fig. 1, and at a point as represented by sectional line 1 and 2 in Fig. 1, showing the different layers of wire, and also sections of the segmental parts of the arms a a, the armature L, the barrel or cylinder d of the coil, and the space b between the arms for the play of the armature. Fig. 9 is a vertical section of the largest of the two sounders, taken at a central point and at right angles to its horizontal plane.

Figures and letters of reference indicate different parts, with their connections, in each figure, which will presently be described in a more detailed manner.

My invention consists in certain improvements in magnets, sounders, and relay-magnets, whereby I reduce very materially the

amount of battery necessary to effect any given desired amount of magnetic force, and I am enabled to operate effectively these sounders when placed directly on the main line, without the use of relays or local batteries, as heretofore deemed generally necessary.

To enable others skilled in the art to make and use my invention, I will proceed to describe in detail its construction and operation, which are as follows:

First, the coils J J, Fig. 1, are constructed of three layers or portions of wire of two different sizes. The figures 1 1 in Figs. 3 and 8 represent two layers of larger size or coarse wire, and 2 in the same figures a layer of finer wire; the sizes of wire employed to be at the option of the manufacturer of the coils. In Fig. 1 two coils are arranged end to end, instead of in the ordinary way, parallel, and mounted each upon the two segmental terminations or arms of soft iron attached to and forming parts of the two cores, as shown in Figs. 4 and 5. Although two coils are arranged in this figure, only one may be used and the armature passed entirely through and suspended at each end.

The core of my magnet, and the most peculiar feature of it, consists of two parts, plans of which are shown in Figs. 4 and 5, and end views of the same, in Fig. 2, (marked H G,) and further details in Figs. 7 and 8, (marked 10 and 12, and a a.) Fig. 5 is one part, which I call "electro" or "soft-iron" part, formed nearly in an oblong shape, with a slight opening at one side. The open side is constructed of two segmental pieces, which I call "arms," "terminations," or "extremities," (marked W W W W',) on which are to be placed the coils. These arms are connected with the two short sides of the U-shaped bar and secured by screws, (marked P P in Figs. 2, 4, and 5,) the only reason for forming these joints being convenience in construction. The other part of the core, a plan of which is represented at Fig. 4, is all of steel, except the two segmental or half-round arms W W W W', which are soft iron. In shape and size, up to the arms, this steel part is the same as the soft-iron part, the only difference being that, for convenience two thin plates, k k', secured by brass screws at T T, Fig. 4, are combined, as seen in the end view at X

in Fig. 2. Above the arms it is different from the soft-iron part. Instead of terminating at the arms W W, the outside plate of steel is continued on farther, as at 9 in Fig. 2, and another U-shaped piece, F, Figs. 2 and 4, slotted at each end and secured by screws *e d e d*, forming a figure (if the arms W W were removed and the part 9 were not bent at right angles with the part G) something like a square, which might be extended by means of the slotted connections into an oblong square. These two parts of steel F and G are hardened and charged with magnetism. An end view of this steel part, with its connections, may be seen at F G in Fig. 2. In this figure it is represented as assuming a perpendicular and also a horizontal position. It is bent over to one side of the coils in this manner only to escape coming in contact with the arrangement of the sounders, &c., above. The object of forming this steel magnet of two parts with a slotted connection is two-fold. First is for the purpose of presenting a perfect circuit to retain the permanent magnetism so employed, and that time and action shall not diminish its force; second, that the magnetic force in practice may be concentrated or diffused at pleasure, by reducing in the former case, or enlarging in the latter case, the magnetic circle, as the U-shaped bar, before described, is moved through its slot inwardly toward the core, or withdrawn outwardly from the core. These two parts, the steel, Fig. 4, and the soft iron, Fig. 5, are placed together, Fig. 2, the insulator U between and secured by two brass screws, (marked *s s* in Fig. 1,) and the whole secured by screws *u u* set in a groove or mortise cut in a base, I, Fig. 3, hollowed out at the bottom and mounted upon round knobs or legs at the corners.

The soft-iron arms W W in Figs. 2 and 4 and W' W' in Figs. 2 and 5 are arranged with their flat surfaces face to face, two on a side, and their segmental or half-round surfaces outside, with the space between forming a cylindrical shape to fit the hollow in the coil, as at *a a* in Fig. 8, presenting an open space or slot between them all the way through the coils, in which space or slot the armature L, Fig. 1, is placed, a side and lengthwise view of which may be seen at L in Fig. 3, and an end view, with the space *b* for its vibration, in Fig. 8.

The armature is of soft iron and extending nearly or quite the whole length of both of the coils, with small brass rivets *v v v v* in Fig. 3 at each corner, the heads of which project a trifle, for the purpose of preventing the iron surfaces of the armature and those of the arms from coming in contact. It is attached by a screw in the center upon an axle, *g*, Fig. 3, oscillating in adjustable screws *h h*, Fig. 3, supported in the bearings shown in section in Fig. 3, front and end views at Figs. 1 and 2, and in plan at Fig. 6. At the opposite end of this lever from the armature is attached the hammer M, which strikes the sounders, or rings

a bell, or breaks and closes a circuit of electricity, accordingly as applied.

In Fig. 1 A and B are two sounders, and an end view is given in Fig. 2, and a sectional view of one is represented in Fig. 9. They are arranged facing each other and at right angles to the vibrating plane of the hammer, which plays between and strikes against their faces.

Bells to give alarms, or any suitable contrivance for making a noise or sounds, or points may be properly arranged for breaking and closing a circuit substituted in their place, and adjustable screws are affixed, as at *f a h* in Fig. 2, for the purpose of moving the sounders nearer to or farther from the face of the hammer, and thereby diminish or enlarge at pleasure the distance through which the hammer is moved, and shifting the sounders, accordingly as a weak or strong current of magnetism is being employed.

The bowls of the sounders are mounted upon suitable posts, as at *i i* in Fig. 2, and may be made of any kind of hard wood, ivory, bone, rubber, or any kind of material suitable for the purpose, with a face made of steel, ivory, or any suitable hard substance answering the purpose, and secured to the hollow part by a screw, *c'*, and nut *d'*, Fig. 2, the upper edge of the bowl to be a little beveled away, and an opening at the top, (marked 15 in Fig. 1.) The face-plate is of the same diameter, or nearly so, as that of the bowl, and is raised a little above the top of the bowl, so that the bottom may hang clear (see Fig. 3) and the screw *c' d'*, Fig. 2, put about a third of the way from the top to the center of the bowl, and immediately, or nearly so, on a line perpendicular to the center of the opening at the top above described.

The tone or sound may be regulated by tightening or loosening the screw *c' d'*, Figs. 2 and 9. One of these sounders is made a little larger than the other, for the purposes of distinguishing the forward and backward stroke of the hammer, or to designate the open and closed circuits. The posts *i i*, Fig. 2, mounting the sounders, are secured to a sliding movable piece, E, Fig. 2, which is attached to part E', Fig. 6, by means of a screw, *e s*, Fig. 2, working in slot *e' s'*, Fig. 6, and the other side by the screw *m* in Fig. 2, and the whole, with the armature-axle bearing-piece E', Fig. 6, mounted on and secured to post K, Fig. 2. The adjustable-screw *m* in Fig. 2 passes through the upper section of post K in a proper thread, with one extremity made to revolve in post *i*, Fig. 2, and by means of shoulders to move post *i* and its fixtures, already described, inwardly or outwardly from a center line, and change accordingly the angle of the space through which the bell or sounder and the armature below it moves under the magnetic forces. This screw *m*, together with the permanent or induced magnetism in one part of the core, (the magnetism serving in the capacity of the spring and the screw as a means of regulating the

same,) is a substitute for the spiral or other spring heretofore used for adjusting the armature of an ordinary magnet.

Points for breaking and closing a circuit of electricity may be combined with, or may be substituted for, the sounders, if desired, or bells to give alarms may be similarly arranged, or any suitable contrivance for making a noise or sounds.

It will be seen that the armature of this magnet is placed in the central part, and extends nearly—and may entirely, if necessary—the entire length of the coils, and it may be farther extended and arranged to receive the magnetic force in the projections of the cores beyond the plane of the ends of the coil, even to the completion of a circle, and that its movement is exactly, or nearly so, at right angles to the direction of the movement of the armatures of the ordinary magnets, and that its motion is laterally, or in the same direction as that of the circuit of electricity or wire on the coils, instead of the ordinary way.

The magnetic influence in the soft-iron arms attached to the steel part of my magnet is caused by the induction of the permanent magnetism in the direction marked by the arrow 1 in arm W, Fig. 4, instead of following the whole circuit of bar F in the direction of arrow 2.

The polarity of the magnetism in the steel must be adjusted with a proper regard to the direction of the winding of the wire upon the coils, and also the direction of the current to be passed through or around the coils, so that when the current or circuit is closed through the coils the influence upon the permanent magnetism shall be to turn it back or disperse it from the arms to the steel. When the circuit is withdrawn from the coils the induced magnetism from the steel, through the soft-iron arms attached thereto, attracts the armature to that side, and when the circuit is closed through the coils the attractive influence on the soft-iron arms of the steel is neutralized and the soft-iron arms of the opposite side of the armature assumes the attractive power,

and the armature is carried over to that side, &c., so that the two sides of the same core in the same coil and with the same current are affected in two ways, and in a direction contrary or opposite to each other; or, in other words, one side of the core is caused to attract the armature when the current is passed into or around the coils, and the other side of the core attracts the armature when the current is withdrawn from the coil. Thus the one set of soft-iron arms becomes an electro-magnet under the influence of the current, while the other set of the soft-iron arms ceases to be a permanent magnet under that influence.

Having thus described my invention, I will proceed to state what I claim as new and desire to secure by Letters Patent, to wit:

1. The mode above described of making the magnets, consisting of the parts G F W W and H W' W', as and for the purpose specified.

2. The mode above described of constructing and arranging the armature L and lever j with reference to the coils and cores, in combination with the adjustable screw π , as set forth.

3. The above-described mode of combining sounders and the several parts thereof with the adjustable screws and movable base, to regulate the stroke of the hammer and to adapt such sounders to the varying strength of the magnetic forces that may be working the armature, as above specified.

4. The use in magnets of bells or sounders of different sizes—that is, one smaller than the other—as and for the purpose set forth.

5. The sliding movable bar F, Fig. 4, with its slotted connections, as and for the purpose set forth.

6. In the construction of a magnet, the use of the parts described—viz., G F W W and H W' W'—in combination with the armature L, lever j, and bells or sounders A and B, as and for the purpose specified.

S. F. VAN CHOATE.
